UNITED STATES PATENT OFFICE.

ADELBERT P. HINE, OF WOODBURY, CONNECTICUT.

SPINNING-RING.

1,226,661.

Specification of Letters Patent. Patented May 22, 1917.

Application filed December 31, 1914. Serial No. 879,875.

To all whom it may concern:

Be it known that I, ADELBERT P. HINE, a citizen of the United States, residing in Woodbury, in the county of Litchfield and 5 State of Connecticut, have invented certain new and useful Improvements in Spinning-Rings, of which the following is a specification.

This invention relates to that class of 10 rings which are used in the art of ring spinning, and which are provided with tracks or guide surfaces for the thread-carrying "travelers." Owing to the high-speed of the travelers,—commonly reaching eight- 15 thousand revolutions per minute,—these rings require their track-surfaces to be made extremely hard, and also extremely smooth. And owing to the short life of the rings, whereby the consumption of them ag- 20 gregates many millions per annum, the requirements of the trade have become most exacting, not only as to relative durability and precision, but also for a greater value with a reduced cost. It is, therefore, the 25 object of my present improvements to furnish a spinning ring having superior operational qualities, and one which, while adapted to be made of sheet or plate metal, shall also have a simple construction in 30 which the track-surfaces will be formed on one surface only of the metal, while the sectional form shall be such as to favor the necessary hardening and polishing operations with a minimum impairment and def- 35 ormation of the metal.

In the accompanying drawing, Figure 1 is a plan view,—shown partially broken away,—of a sheet-metal spinning ring made in accordance with my present invention.

40 Fig. 2 is a vertical section in line 2, 2, of Fig. 1.

Fig. 3 is a sectional view similar to Fig. 2, for illustrating a modified arrangement of certain features.

45 Fig. 4 is an enlarged transverse section of the ring, as shown in the left-hand portion of Fig. 2, for more fully illustrating the track-zone locations and the relation of the ring-head to a traveler carried thereon.

50 Fig. 4^a is a partial plan view as seen from above in Fig. 4, these two figures being drawn in alinement to facilitate comparison thereof.

Figs. 5 and 6 are views similar to Fig. 4, 55 for illustrating certain features in modified

arrangements, as hereinafter more fully explained.

Similar characters designate like parts in all the views.

In Figs. 1, 2 and 3, the hollow ring head is designated by H, the annular web by N, and the base, or base-flange, by B. In Fig. 2, the inner portion of the hollow head H is shown joining the web N, while in Fig. 3, that arrangement is reversed; so that here 60 the outer portion of the head (here designated by H') joins the web N; of these two arrangements, the one shown in Fig. 3, is also shown in Figs. 4 and 5, while the arrangement of Fig. 3 is the one shown in Fig. 6. In Figs. 1, 2, 3, 4 and 5, some space 65 is indicated at S, but the proportionate amount of this space may be varied. In Fig. 5 the modified form of the head H is further distinguished by H², and, similarly, 70 in Fig. 6, by H³. In each form of the head H, this member has an interior space, C, so that at no point is there any doubling or 75 folding of any part of the sheet-metal upon another part thereof.

The web N, of the ring preferably consists of an annular member and is herein shown made of a single thickness of metal. On the lower edge thereof, the web N joins with a base member, as B, which is preferably of the form (substantially as shown) 80 of an outwardly-extending flange having,—relatively to the height of the web,—a considerable width radially of the ring, this being the arrangement herein illustrated in 85 all the views. In this construction, the base-and-web portion of the ring is in the nature of an annular device having in section an L-shaped form (Fig. 4), and having the section so proportioned as to afford 90 a high degree of stability and resistance to injury, with a minimum of metal, and of cost of manufacture.

95 On its upper edge, the web N is shown reinforced and stiffened in a corresponding 100 manner. The juncture at the angle or bend 2, of the web N, integrally joins the web with the head H, and in a direction laterally thereto at the line of said juncture, so that by such angular construction, each said part 105 operates as a stiffening member for the other. Thus the immediately adjacent and combined portions of the web and head have substantially an L-shaped form, while the base and web, together with that part of 110

the head which is contiguous to the web, form a section having a so-called Z-shape, which is a construction having peculiar and important advantages, especially in a spinning-ring consisting of sheet-metal, and having the head thereof of the hollow formation herein set forth. In this preferred arrangement, as shown in Figs. 2, 4, and 5, the angle-portions at 2 and 3, are located in reversed directions, respectively; this provides for direct and free access to the interior of the angles by tools used in finishing the rings, and, later, for polishing and cleaning the hardened rings.

15 The "ring" proper may be said to comprise the traveler-tracks, and these may consist of arcs or segments, each having a similarity of relation to a geometric center or axial line. In Figs. 2, 4, 4^a, those arcs or zones comprise the outer-track surface, or track-zone, 4, and the inner track-surface, or track-zone, 5, and these arcs or zones are each shown of the form of a circular-arc, and, also, each said arc is of a similar radial distance from the center-point, or axial line α . These respective radial distances may, however, be varied, and be unlike in measurement, without changing that similarity of relation which consists in the concentricity relatively to said axial line, which is located within the space C, of the hollow head-portion H, of the ring. Such an arrangement is illustrated in Fig. 5, where the respective track-zones or segments 4 and 5 are each concentric with relation to the axis α , although one said segment has a curvature different from the other.

In Fig. 4, the head is shown in transverse section, and in the form of ring shown in this figure, the inner and outer track-zones 5, 4, are of convex curvature outwardly relatively to the axis α , and constitute integrally-connected single-thickness parts of a head-section which is of a continuous curvature throughout the sectional circumference thereof. These features are also found in a somewhat modified form, in the constructions illustrated in Figs. 5 and 6, as will now be evident.

50 One feature of my present improvements is the provision, on the head of the ring, of two oppositely-disposed track-zones each having in the plane of the ring axis, a convex curvature throughout the width thereof.

55 One of these track-zones, as 4, is the outside track, while the opposite said zone, as 5, Fig. 4, is the inside track. In the preferred form and arrangement, each of said zones is in the form of a segment which, (as indicated in the enlarged sectional view Fig. 4), constitutes a part of a head member that in section is of a continuous curvature throughout the cross-sectional extent, or circumference thereof. In the form shown in

60 Fig. 4, this continuous curvature is substan-

tially uniform throughout the circumference of the head H, so that the outer track-segment 4 is connected with the inner track-segment 5, by an intermediate portion, or top-zone, as 6, having the same curvature as the track-zones. Thus the head member may have, not only a continuous, and, externally, a convex and outward curvature throughout the cross-sectional length, or extent thereof, but this curvature may be uniform in amount in all parts of that length, and the oppositely-located segmental portions thereof may constitute bearing-zones which are of equal convexity the one with the other.

A further feature of the forms of ring-head as shown in the drawing, is that the head may have the metal in all portions thereof, curved in two directions, and in directions substantially transverse to each other in any one part of the ring-head. For instance, in Fig. 4,—when compared with Figs. 1 and 4^a,—it will be seen that each part of the outer track-zone 4 is curved convexly as regards a plane transversely of the ring-axis α , and is also curved convexly relatively to, or in, a plane at right-angles to said axis, (as seen in plan view), and thus has a double-convexity. On the inner track-zone, however, the metal, while curved convexly in a plane transversely of the ring-axis, is concavely curved as seen in plan view. The outer zone 4, therefore, may be said to have two outward convexities, while the inner zone 5 has one convexity transversely, and one concave curvature as seen in the plan views. Thus the ring-head has inner and outer zones having respectively, unlike combinations of pairs of curvatures, of which one pair is located in a reversed arrangement relatively to the other pair.

The construction here described has the important advantage that during the forming processes the metal in the head H, is subjected to a forming-action which throughout the head, is of a minimum degree of variation, and which therefore leaves the metal of the entire head-portion of the ring with the highest degree of uniformity, and with a minimum degree of structural or molecular impairment. One object of this construction is to obtain by means of qualities here pointed out, a corresponding uniformity of result when the rings are later subjected to the operations of hardening and polishing. Since the exterior track-zone surfaces require extreme hardness, the uniformity of the metal in the head, tends materially to secure uniformity of surface hardness and texture, and also tends to reduce to a minimum the distortion and breakage ordinarily resulting from the heating and hardening processes. These losses are frequently excessive, and even under favorable conditions have heretofore

been sufficient to materially increase the cost of manufacturing spinning rings of the ordinary kinds, besides decreasing the average life of the usable product of such manufacture.

From a comparison of Figs. 4, 5 and 6, it will be seen that in each of the forms which are therein illustrated the two track-surfaces are located on the same side, or surface, of the metal. Hence, in practice, one side of the metal while this is in sheet-form, may be finished and polished to a high degree of smoothness, and the sheet may then be wrought into rings by the aid of highly finished dies and tools, so that subsequently to the hardening, only a slight degree of re-polishing will be required.

In the forms shown in Figs. 5 and 6, the ring-section may be said to comprise two arcs, preferably circular, which, though on different radii, are substantially concentric (especially when they are circular arcs) to the same center, as α . The traveler, as T, is non-reversible, being incapable of being put into any working position, unless applied in one and the proper way. This feature permits of a construction whereby to minimize the so-called wedging-action which normally occurs to some extent when the ring-section is made up of circular arcs of equal radii, as in Fig. 4. In Figs. 4, 5, 6, the approximate direction of the draft of the thread, is indicated by the arrows 7, while in Figs. 4, 4^a, an ordinary arrangement, (or position) of the thread is indicated by 8. In Fig. 4^a, the thread 8 is shown running to a bobbin located at 9, centrally of the ring, in a well-known manner. The improved constructions of the traveler T, which are

herein shown for more fully illustrating the construction of the ring, are not claimed herein, but are reserved to constitute in part the subject-matter of a separate application to be concurrently pending herewith.

Having thus described my invention, I claim:

1. A spinning ring comprising a hollow head having integrally-connected inner and outer track-zones which in transverse section are curved in opposite directions, respectively, one of said track-zones having the transverse curvature thereof greater than such curvature of the other said zone, and said track-zones being each located concentrically with relation to one axial line within the space of the hollow ring-head.

2. A spinning ring comprising a hollow head having integrally-connected inner and outer track-zones which in transverse section are curved in opposite directions, respectively, and each with an outward convexity, said outer track-zone having the transverse curvature thereof greater than such curvature of the inner said zone.

3. A spinning ring comprising a hollow head portion having inner and outer track-zones which in transverse section are curved in opposite directions, one of said track-zones having the transverse curvature thereof greater than such curvature of the other of said zones in combination with a loop-form traveler having converging curved ends which respectively are adapted to bear on said track-zones of the ring.

ADELBERT P. HINE.
